UNITED STATES PATENT OFFICE.

SALVATORE J. ZAMMATARO, OF BROOKLYN, NEW YORK.

COLLAPSIBLE TUBE.

Application filed October 8, 1925. Serial No. 61,176.

This invention relates to containers for viscous or fluid materials, and is particularly well adapted for shaving creams and similar substances.

5 Its object is to provide a tube wherein, when pressure is applied thereto, the stopper is automatically removed from the discharge outlet and a quantity of the contents is expelled, dependent upon the length of 10 time the pressure is applied, and upon the removal of such pressure the stopper automatically resumes its normal position, closing the discharge outlet and preventing further removal of the contents until pressure is again applied.

Referring to the drawings,

Fig. 1 is a plan view of one form of my invention;

Fig. 2 is a longitudinal section on the line 20 1—1 of Fig. 1;

Fig. 3 is a longitudinal section in a modified form of the invention;

Fig. 4 is a longitudinal section on the line 4—4 of Fig. 5 showing another modification;

25 Fig. 5 is a plan view of the modification shown in Fig. 4; and

Fig. 6 is a longitudinal section of still another modification.

Referring to Fig. 2, the body 10 of the 30 tube terminates at its upper end in a constricted head 11 having a discharge opening which is closed by a plunger 12. This plunger is slidably mounted on an annular socket portion 13, together with which it 35 confines an air chamber in which is housed a coiled spring 14. This spring is normally under an initial compression sufficient to force the plunger against the edges of the discharge opening. While the aperture is 40 shown circular in form, it is obvious that it may be of any desired shape. The socket 13 is carried by a support 16 integral with, and which extends transversely of, the tube, and as shown most clearly in Fig. 1, this 45 support is provided with a series of holes 15 for the passage of the contents from the body of the tube to the chamber formed between the support 16 and the top of the tube. When pressure is applied to the body portion 50 of the tube, it is transmitted through the contents equally in all directions with a resultant force acting on the plunger 12 to further compress the coiled spring 14. The plunger in moving downwardly opens 55 the aperture and the paste is expelled from the tube and onto the article with which it is to be used, for example, a tooth brush.

The paste will flow out of the tube only as long as pressure is applied, and when pressure is released the plunger 12 will be restored to its seat by the coiled spring 14. 60 Thus, the aperture is automatically opened and closed, the amount of paste expelled being controlled by the pressure applied to the tube, the plunger automatically opening 65 and closing the aperture in the tube, thus obviating the use of screw caps.

In the modification shown in Fig. 3, instead of the plunger sliding on a socket as in Figs. 1 and 2, the lower rim 17 of the plunger 18 has attached thereto one end of 70 a flexible tubular member 19, the other end of said member being anchored to the transverse perforated support. In this construction, the friction between the plunger 12 and the annular member 13 of Fig. 2 is avoided. 75 This construction also prevents any possibility of the contents entering the air chamber containing the spring. In this construction the coiled spring 21 acts similarly to the coiled spring 14 of Fig. 2, but instead of the 80 plunger riding on the annular member 13 as it is depressed, the tubular flexible member 19 collapses against the compression of spring 21 as pressure is applied to the tube, and when pressure is removed the spring 85 reseats the plunger and extends the member 19.

In the modification shown in Figs. 4 and 5, the upper end of the tube 22 is made of corrugated springy material which takes the 90 place of the coiled spring of Figs. 2 and 3. In this modification the stopper 25 is not movable but, instead, as pressure is applied to the tube, the contents are forced through the openings 23 in the transverse support 24 95 and against the parts 22 and 26, stretching the part 22 which thus permits part 26 to move upwardly under the pressure of the contents with the result that an outlet for the contents is provided between the tapered 100 end of the stopper 25 and the aperture of part 26. When pressure is removed from the tube, the flexible part 22 restores to its normal position, closing the discharge outlet.

Referring now to Fig. 6, in this embodiment of the invention the transverse partition is provided with a central opening through which the plunger 29 reciprocates. This plunger is hollow and has anchored thereto a corrugated spring in the form of 110 a membrane 28, which is anchored at its outer periphery to the tube wall. Extending longitudinally of the plunger above the

membrane 28, are slots. The plunger at its upper end normally closes an aperture in the top of the tube. In this construction pressure applied to the tube forces the paste through the hollow plunger, out of the slots therein into the upper chamber 30, and forces the membrane 28 and the plunger attached thereto downwardly. The plunger in moving downwardly provides an opening 10 in the top of the tube through which the paste is expelled. When the pressure is removed, the spring member 28 in returning to its normal position moves the plunger upwardly to close the discharge opening. 15 While several specific embodiments have been shown as illustrative of the invention, it is to be understood that the invention

may take other specific forms, being only limited by the appended claim.

20

I claim:

In combination, a tube having an opening in its head, a plunger, a transverse partition in said tube, a spring seated on said partition and engaging said plunger to force the same against said opening, said partition having perforations near its periphery providing a passage for the contents of the tube, and means carried by said partition and plunger for preventing access of the tube contents to the under side of said plunger. 25 30

In witness whereof, I have hereunto subscribed my name this 6th day of October, A. D. 1925.

SALVATORE J. ZAMMATARO.
